UNITED STATES PATENT OFFICE

FRED R. BELT, OF CHICAGO, ILLINOIS

ASH RECEIVER

Application filed April 16, 1928. Serial No. 270,168.

This invention relates to ash receivers and its primary object is to provide an ash receiver which may be detachably clamped to a card table or other piece of furniture and moved into and out of operative position as required.

Another object is to provide an ash receiver comprising a receptacle in the form of a cup which may be swung out of the way and concealed under a table ledge or the arm of a chair when not in use and swung out from under the ledge or the arm when required for use.

In the accompanying drawing illustrating a selected embodiment of the invention, the views are as follows:

Fig. 1 is a top plan view of my novel ash receiver applied to a table ledge.

Fig. 2 is a side elevation of the device shown in Fig. 1 on an enlarged scale.

Fig. 3 is a transverse sectional view on the line 3—3 of Fig. 2.

Fig. 4 is a detail plan view on the line 4—4 of Fig. 3.

Fig. 5 is a detail perspective view of one of the parts.

Fig. 6 is a detail elevation of another part.

Referring to the drawings, 10 designates a tubular post provided with an elongated slot 11 in one side and a clamping arm 12 rigidly connected to the top thereof. A slideable arm 13 provided with an annular collar 14 is adapted to slide on the post 10. A center lug or core 15 is arranged in the collar 14 and is connected to one side thereof by a web 16. The post 10 fits into the collar 14, and the core 15 fits within the post 10, the web 16 sliding within the slot 11. This construction keeps the arm 13 in proper position relative to the post, and the parts are so constructed that when the slideable arm 13 is applied to the post, the arms 13 and 12 will be opposite and spaced from each other as shown in Fig. 2. The post 10 is screw-threaded at its lower end to receive a cap 17, Fig. 3.

A spring 18 is arranged within the post 10 and is confined between the cap 17 and the bottom of the core 15 to normally urge the arm 13 upward on the post 10. A thumb-

piece 19 is connected to the side of the collar 14 to enable the spring to be compressed when the device is being clamped in position. The parts just described comprise a clamping member which may be detachably applied to a piece of furniture such as a card table 55 20, Figs. 1 and 2. Rubber disks 21, or other soft material, are arranged on the arms 12 and 13 to prevent marring of the table when the clamp is applied. The arm 12 may be concave at 22 to conveniently hold a cigar or a cigarette.

The collar 14 has a lug 23 integral therewith which is spaced substantially at right angles to the thumb-piece 19. The lower end 65 of the lug 23 may be elongated at 24, Figs. 3 and 5, and an aperture 25 provided therein receives a pivot pin 26 which is embedded in an ear 27 integral with the annular flange 28 at the side of the receptacle or cup 29.

In practice, arm 13 is slid on the post 10 and urged toward the arm 12 by the spring 18. By pressing on the cap 17 and the thumb-piece 19 the spring is compressed and the arm 13 is moved vertically on the post 10 to space the arm 13 from the arm 12 so that the device 70 may be easily applied to a table ledge or to the arm of a chair. When the thumb-piece is released, the spring 18 securely keeps the two arms in clamped position. The pivot pin 80 26 is then inserted in the aperture 25 of the lug 23 to pivotally support the cup on the lug 22. The cup may then be swung inwardly on the pin 26 and concealed under the table when not in use and then swung outwardly when required for use. The various parts of my device embodying the present invention may be made of metal or any other material.

My present invention provides an ash receptacle which may be detachably supported on a piece of furniture without marring the same and which can be easily and quickly operated to bring it into use and then moved away and concealed when not required.

Changes may be made in the form, construction and arrangement of the parts without departing from the spirit or scope of the invention or sacrificing any of the advantages thereof, and I reserve the right to make all 95 100

such changes as fairly fall within the scope of the following claims.

I claim:

1. In an ash receiver, the combination of a support comprising a tubular post, a rigid clamping arm on said post, another clamping arm movable on said post, a spring within the post acting upon the movable arm for cooperating with the rigid arm to clamp the post upon a table, a lug on said movable arm projecting outward at an angle to and below the top thereof, and a cup pivotally engaged with the lug and adapted to be swung about the lug under the movable arm and table or outward from the table.
2. In an ash receiver, the combination of a support comprising a tubular post, a rigid clamping arm on said post, another clamping arm movable on the post, a spring within the post acting upon the movable arm for cooperating with the rigid arm to clamp the post upon a table, a lug on said movable arm projecting laterally therefrom and having a pivot opening, a cup and a pivot pin on the cup, and detachably engageable with said opening for swinging movement under the movable arm and table or projecting outward from the table.
3. In an ash receiver, the combination of a support comprising a tubular post having a slot in its side, a removable cap on the lower end and a rigid clamping arm on the upper end of said post, another clamping arm having a collar, said collar being movable on the post and having a core within the post and a connecting web in the slot, a spring confined within the post between the cap and the core, a lug on the collar, and a cup pivotally and detachably engaged with the lug and adapted to be swung under the movable arm and table or outward from the table.

FRED R. BELT.
